[57] CLAIM

The ornamental design for destaticizing blower, as shown and described.

DESCRIPTION

FIG. 1 is a perspective view taken from the top, front and right side of a destaticizing blower showing my new design;

FIG. 2 is a left side elevational view thereof;

FIG. 3 is a top plan view thereof;

FIG. 4 is a front elevation view thereof;

FIG. 5 is a rear elevation view thereof; and

FIG. 6 is a bottom plan view thereof.

It is understood that the pattern of openings is continuous throughout the area indicated in FIG. 5.
